UNITED STATES PATENT OFFICE.

WALTER J. WILSON, OF SEWICKLEY, PENNSYLVANIA.

CUTTING APPARATUS FOR MINING MACHINES.

Application filed November 18, 1918. Serial No. 263,059.

To all whom it may concern:

Be it known that I, WALTER J. WILSON, a citizen of the United States, residing at Sewickley, in the county of Allegheny and State of Pennsylvania, have invented certain new and useful Improvements in Cutting Apparatus for Mining Machines, of which the following is a specification.

This invention relates more particularly to mining machines of the cutter chain type. In these machines, as ordinarily constructed, the chain passes through a guide which holds it rigidly up to its work, so that each bit travels in a substantially straight line, making a cut similar to that of a planer tool. When a miner cuts a kerf with a pick, the cutting operation is quite different from that of the bits as thus described. He usually makes a slight arc-shaped cut with his pick, which means that the finish of the cut is outwardly or toward an open end. He then makes another similar cut in advance of the first one, thus leaving a spandrel-shaped, or triangular, space between the two cuts. This projecting portion of coal is then easily broken out by the next stroke of the pick. By repeating this operation at the top and bottom of the kerf, the intermediate portions are more readily excavated. The present invention relates to a cutting apparatus which is intended to somewhat simulate this method of cutting or excavating as done by a miner.

The objects of this invention are to provide an improved and efficient form of cutting apparatus for mining machines; to provide a cutting apparatus of the chain type in which the bits may move along irregular lines between the supporting wheels; to provide an improved chain guide for mining machines; to provide a plurality of cutter chains arranged adjacent to each other, each chain having guide means whereby the bits of one chain may be forced forwardly at points intermediate to those at which the bits of the adjacent chain are forced forwardly; to provide a plurality of cutter chains arranged adjacent to each other and adapted to coact in cutting a relatively wide kerf, said chains being supported by guides whereby they may be arranged at various positions with respect to each other, and whereby the portions of one chain may cut in advance of portions of another chain; and in general to provide such advantages

and improvements as will be described more fully hereinafter.

In the accompanying drawings illustrating this invention:

Figure 1 is a side view of a cutter arm and chain, embodying this invention;

Figure 2 is a cross sectional view taken on the line 2—2 of Fig. 1;

Figure 3 is a fragmentary longitudinal sectional view;

Figure 4 is a side view showing the arrangement of a plurality of chains which are arranged adjacent to each other, and are supported on wheels of the same size;

Figure 5 is a cross sectional view taken on line 5—5 of Fig. 4;

Figure 6 is a side view showing the arrangement when the chains are supported on wheels of different size;

Figure 7 is a plan view of the apparatus shown in Fig. 6;

Figure 8 is a cross sectional view taken on line 8—8 of Fig. 6; and

Figures 9 and 10 are cross sectional views showing modified arrangements of the chains.

In all of these figures the parts are shown more or less diagrammatically, and parts are omitted for convenience in illustration.

My invention is applicable to the various types of mining machines now in use, such as breast machines, long wall machines, short wall machines; and is particularly applicable to mining and loading machines of the character shown in my co-pending application Serial No. 195,560, filed October 9, 1917.

Figs. 1 to 3 illustrate the invention as applied to the cutter arm of a short wall machine. As shown in these Figures, 11 represents a cutter arm having a driving sprocket 12 at one end, and a guide wheel 13 at the opposite end, it being understood that this end is the one which enters the coal or other material to be excavated. The bar or arm is provided with a rear chain guide 14, which may be of any ordinary construction. The front chain guide 15 embodies the principal novel features of this invention. Instead of guiding the chain in a straight longitudinal line, this guide is constructed so as to guide the chain in a curved or wavy line. This is readily accomplished by inserting cam-like lugs or projections 16 in the bottom of the guide channel

15. These projections or inserts may be held in any suitable manner, as by means of rivets 17. These cams or inserts are curved or tapered, as shown in Fig. 3, and are preferably arranged so that the highest points are separated by a distance equal to approximately four links of the chain 18, or so that when two of the bits 19 are at these elevated points, the intermediate bit will be halfway between them. While I consider this the best arrangement, it will be noted that the spacing of the elevated portions may be varied if desired. For certain types of machines now constructed, these elevations may 10 be about one-fourth of an inch in height and approximately ten inches from center to center. It will also be noted that a curved or waved guide may also be constructed in different ways to conform to this invention, 15 but the arrangement described provides a simple method of construction.

The operation of this apparatus, as thus described will be readily understood if the cutter arm is considered as having made its 20 sumping cut and is moving forwardly. It will be understood that the forward or feeding movement of the cutter bar causes the guide to press the chain 18 forwardly so as to hold the bits 19 in cutting engagement 25 with the coal. With my improved guide, each bit may be considered as making an arcuate cut, as indicated at 20 and 21 in Fig. 3, as each link passes over the corresponding projection 16. It will be noted that 30 the bit in making the latter part of the cut moves toward the kerf or toward an open face, so that the coal will be broken out more easily when the bit is making a straight longitudinal cut and always working 35 against the coal. When the bits have made the arcuate cuts as indicated at 20 and 21, the intermediate projection, indicated at 40 22, is then more readily cut or excavated, as the bit is then cutting toward the opening made by the arcuate cut in advance 45 thereof. The exact cutting operation of each bit will, of course, be somewhat modified by the forward movement of the bar, but the general action is substantially as above described. It will be seen that by means of 50 this arrangement, much of the cutting is done toward the kerf or toward an open end, whereby the cuttings will be more easily excavated and will be larger than usually 55 made with the ordinary chain cutter.

While the preceding description has referred to an undercutting machine, it may also be considered as applicable to a mining and loading machine adapted to cut a vertical kerf.

Figs. 4 and 5 show a cutter bar having a plurality of chains, and constructed particularly for a cutting and loading machine.

In this instance the cutter bar 23 is provided with a plurality of chain guides 24,

25 and 26. These guides are provided with flanges 27 at their upper edges so as to form a substantially continuous surface for conveying the material. The projections 16 are placed in staggered relation in the different 70 guides, so that when the bits of one chain are in raised position, the bits of the adjacent chain may be in depressed position. This will further assist the excavating action, as when the bits of the central chain are cutting certain portions of the material, the bits of the adjacent chains will have previously made cuts at the sides of such material, so that it will be more readily cut or broken away. With this arrangement, the 75 excavated material is carried back by the chains along the upper guides, so as to form a combined excavating and conveying apparatus.

As shown in Figs. 6 and 7, the cutter bar 28 is provided at the outer end with a large 80 guide wheel 29 for the intermediate chain 30, and with smaller guide wheels 31 for the side chains 32. This arrangement is reversed at the inner end where the intermediate chain 30 is provided with a small driving sprocket 33, and the side chains are provided with larger driving sprockets 34. In this instance, the chain guides are connected 85 by plates 35 to hold the material as it is being conveyed. The elevations on the different guides are also staggered, so that the arcs cut by the bits in one chain will be intermediate of those cut by bits in the adjacent chain. Furthermore, it will be seen 90 that where the two side chains are in advance of the intermediate chain, as shown in Fig. 8, there will be a projecting ledge or rib, as indicated at 36, which will be easily 95 broken away by the bits of the intermediate chain. The operation is somewhat similar 100 when the central chain is in advance of the side chains, as indicated in Fig. 9, as side ledges will be formed which may be readily 105 broken away by the bits of the side chains.

Where a plurality of chains are utilized, they may be positioned in any desired manner with respect to each other, as further illustrated in Fig. 10, in which the side chains 37 are arranged in planes diverging 110 from the plane of the central chain 38.

With my improved apparatus, the cutting under ordinary conditions will be done in an easier manner than with the ordinary cutter chain, and less power will be required 115 while superior cuttings will be produced. It will be particularly noted that when "sulphur balls" or other hard substances are encountered, the cutting action will be expedited, as the bits will then work their way around the hard substance so that it may be dislodged instead of having to be cut through.

Other advantages of my improved apparatus will be apparent to those familiar with 120

this art, and it will be also noted that changes may be made in the details of construction without departing from the scope of my invention. Therefore I do not wish to limit myself to the exact construction herein shown and described, except as specified in the following claims, in which I claim:

1. A cutting apparatus for a mining machine having a continuous chain guide with a waved bottom for the chain.
2. A continuous guide chain for a mining machine, having intermittent projections forming supports for the chain, whereby the intermediate portions of the chain may be pressed backwardly.
3. The combination with a cutter arm for a mining machine and cutter chain therefor, of means comprising a continuous guide for the chain, whereby the chain may move along an irregular path as it travels along the front of the guide.
4. The combination with a chain guide for a mining machine, adapted to form a continuous support for the chain of projections arranged in said guide and adapted to permit the chain to move laterally with respect to the guide.
5. The combination with a chain guide for a mining machine, of a plurality of spaced supports secured in said guide and having curved faces, whereby the cutter bits may be caused to make a series of arcuate cuts as they move longitudinally of the guide.
6. In a mining machine, the combination of a cutter bar, a plurality of cutter chains

mounted on said bar, longitudinal guides for said chains, and projections in said guides arranged in staggered relation in the respective guides, whereby the bits in the respective chains will move laterally with respect to the guide at different points as they move longitudinally of the guides.

7. In a mining machine, the combination of a cutter bar, a plurality of cutter chains carried by said bar, the cutting reaches of said chains being arranged at different distances from a transverse plane through the center of said bar.

8. The combination with a cutter arm, of a plurality of cutter chains mounted in parallel relation on said arm, portions of some of the cutting reaches of said chains being arranged at different distances from a transverse plane through the center of the arm than the corresponding portions of the adjacent chains.

9. The combination of a cutter arm, wheels mounted at each end of said arm, a plurality of chains carried by said wheels, said wheels being of different sizes.

10. In a mining machine, the combination of a cutter bar, a plurality of cutter chains carried by said bar, guide wheels mounted in the outer end of said bar, said wheels being of different diameters.

11. In a mining machine, the combination of a cutter bar, a plurality of chains mounted on said cutter bar, and driving sprockets of different diameters for driving said chains.

WALTER J. WILSON.
